DISPLAY STAND

George Zaninovich, Dinuba, Calif.

Application April 16, 1938, Serial No. 202,367

3 Claims. (Cl. 211—71)

This invention relates to display stands and particularly to a stand for displaying fruit and vegetables, an object being to provide a construction wherein the articles displayed may be arranged in a very pleasing manner and yet the stand may be readily collapsed and dismantled whenever desired.

Another object of the invention is to provide a display stand for fruit and the like wherein the principal parts thereof are arranged in sections so that they may be assembled in small or large groups.

A further object of the invention is to provide a display stand wherein the front part is formed with means for removably receiving display trays and fruit-carrying boxes while the rear part may contain boxes or other articles associated with the business of the person using the stand.

20 In the accompanying drawings:

Fig. 1 is a perspective view of a display stand disclosing an embodiment of the invention, the same being positioned ready for use;

Fig. 2 is a sectional view through Fig. 1 approximately on the line 2—2, suitable fruit-carrying boxes being shown in connection with the stand;

Fig. 3 is a rear view of one section of the stand when collapsed;

Fig. 4 is a front view of the lower part of the left-hand portion of the stand shown in Fig. 1; the same illustrating how the tray and side table are associated with the stand;

Fig. 5 is a fragmentary sectional view through Fig. 4 approximately on the line 5—5;

Fig. 6 is a perspective view of a tray support embodying certain features of the invention;

Fig. 7 is a sectional view on an enlarged scale through Fig. 6 approximately on the line 7—7;

Fig. 8 is a fragmentary view, partly in section, showing how the lower part of the support illustrated in Fig. 6 is disengagably secured to two stand sections;

Fig. 9 is an enlarged detail fragmentary perspective view showing one of the uprights of one of the sections of the stand, together with one of the container supports and a pin identical with that shown in Fig. 8;

Fig. 10 is a perspective view of an arm embodying certain features of the invention;

Fig. 11 is a fragmentary perspective view of the upper part of one of the supporting angle irons of one of the sections showing an elongated slot adapted to receive one of the hooks illustrated in Fig. 10;

Fig. 12 is a fragmentary view showing one of the uprights of one of the stand frames and a modified form of table to that illustrated in Fig. 4;

Fig. 13 is a perspective view of the table shown in Fig. 12 with the supporting arms hanging loose;

Fig. 14 is a modified form of the container support and brace to that illustrated in Fig. 4;

Fig. 15 is a top plan view of the structure shown in Fig. 14, the angle bars being shown in section;

Fig. 16 is a detail fragmentary sectional view through Fig. 4 approximately on the line 16—16 and illustrating how a display tray is bolted to one of the sections;

Fig. 17 is a detail fragmentary sectional view through Fig. 4 approximately on the line 17—17;

Fig. 18 is a detail fragmentary horizontal view through Fig. 5 approximately on the line 18—18.

Referring to the accompanying drawings by numerals, 1, 2 and 3 indicate sections of the stand. Each of these sections is constructed independently so that one or more sections may be used on the stand as may be desired. In Fig. 3 there are shown three sections but it is evident that more or less could be used without departing from the spirit of the invention. As these sections are of identical construction a description of one will apply to all.

From Fig. 1 it will also be noted that there are provided display trays 4, 5 and 6, trays 5 and 6 being arranged between adjacent sections, while tray 4 is arranged at one side of the end section. This necessitates the use of a pair of bracing bars 7 and 8 for supporting a tray, as illustrated in Figs. 1 and 4. These bracing bars or rods are removably fitted into sockets 9 and 10 rigidly secured to the section 1 by rivets or other desired means.

Also, as indicated in Fig. 16, there is provided a bolt 11 for clamping one side of the tray 4 to the tray-supporting bar 12 which is constructed identical with one side of the structure shown in Fig. 6 and which will be herein-after fully described. If desired, the construction may be termed a table 13, which is positioned adjacent the tray. Also, if desired, one or more angle brackets 14 could be secured to the respective supporting legs of the table to assist in supporting one edge portion of the tray.

Instead of the table 13 as shown in Figs. 1, 4 and 5, the table 15 shown in Figs. 12 and 13 could be used. In this form of table there is provided a rectangular housing 16 to which one or more hooks 17 are secured. These hooks extend

- through a suitable bar 18 connected to the section 1. Supporting rods 7' and 8' are used and arranged similar to the bars 7 and 8 but instead of supporting a tray they support the table 15.
- 5 This table 15 may be provided with division members 19 and also with a sliding tray 20 which may be slid out as indicated in dotted lines in Fig. 12 so as to be used as a support when wrapping articles.
- 10 In the form shown in Fig. 1 the table 13 is a rectangular structure and at each corner is provided with a socket 21. The various supporting legs 22 are formed of angle irons with one leg cut off at 23 so that the bottom of the
- 15 table 13 may rest thereon while the extending portion 24 of the leg projects upwardly and into one of the sockets 21. Preferably the portion 24 extends about half way the height of the socket 21 so that a similar extension 25 from
- 20 the two rear legs 26 of the auxiliary table 13' may extend therein as shown in Fig. 5. It will be observed that the auxiliary table 13' is supported by the two rear legs and the two front legs 27, said front legs resting on top of the
- 25 table 13 while the rear legs 26 has one leg of the angle bar cut off at 23 so as to provide the extension 25 and extension 30. The respective extensions 30 fit into suitable sockets 31 which are similar to sockets 21 and are arranged in the table 13'. This table is open at one end similar to table 13 and may be divided by a suitable partition 32. The table 13 may be divided by one or more partitions 33, as shown in Fig. 5. Also there is provided a tray 34 which
- 30 is adapted to be slid outwardly as shown in Fig. 1 so as to present a flat support on which articles may be wrapped. When this tray or support is not desired it is forced inwardly so as to be nested within the table 13 and beneath the
- 35 bottom plate 35 thereon. There is provided a suitable frame 36 bolted or otherwise rigidly secured to the lower ends of the respective legs 22 so as to hold the lower ends properly spaced. Whenever desired the frame and bolts 36 may
- 40 be removed and then the respective tables may be disassembled by pulling the respective legs out of the sockets in the tables. This is done when it is desired to ship the structure from one point to another or to store the same. The
- 45 50 compartments in the respective tables may contain books, paper, twine, or other articles to be used in connection with the stand.
- Sections 1, 2 and 3, as heretofore mentioned, are of identical construction and each of these sections is formed so that it may be arranged as shown in Figs. 1 and 2, or may be readily collapsed as shown in Fig. 3. Each section is provided with a pair of rear uprights 37 and 38. These uprights are of the same height and shape, but upright 37 is provided with a slot 39 while upright 38 is provided with a similar slot adjacent the point 40. The bar or arm 41 (Figs. 1 and 10) is provided with hooks 42 and 43 facing in opposite directions and a notch 44. Hook 43 is adapted to be fitted in the slot 39 in upright 37, but hook 43 is adapted to be fitted in a similar slot in upright 38 at point 40. By reason of this construction scales or other article 45 may be hung on to the arm 41 and be
- 55 60 65 70 75 supported thereby. A similar arm 46 is arranged at the opposite side of the stand and is connected in a similar manner to section 3. This arm 46 may support scales, a bunch of bananas, or other article as preferred.
- Each of the sections is provided with a pair
- of rear uprights 37 and 38, said uprights being preferably of angle iron and coacting with auxiliary uprights 47, 48 and 49, there being two of each of the auxiliary uprights as clearly indicated in Fig. 2. The various uprights are of different lengths so that when the trays 4, 5 and 6 and associated parts are applied they will be at a decided angle whereby fruit or other articles will be properly displayed and yet be ready for removal. Preferably all parts of the sections 1, 2 and 3 are formed of metal and also all the parts heretofore described are formed of metal, though they could be formed of wood or other suitable material.
- All the uprights are connected by a base bar 50 and also by a supporting bar 51, while a supporting bar 52 connects the three rear posts and a supporting bar 53 connects the two rear posts, as clearly shown in Fig. 2. The connections at all points consist of suitable rivets 54 which are sufficiently loose to permit the parts to be collapsed as shown in Fig. 3. At the front there are provided a pair of bracing cross bars 55 and 56 (Fig. 4) which are bolted to the two front uprights 49. All the uprights and the bar 50 are formed of angle iron and each of the supporting bars is provided with a turned-up end 57 which acts as an abutment for preventing a container 58 from sliding off the section. Extending laterally from one side bar to the other are bracing bars 59, 60 and 61. Each of these bracing bars is provided with a tube or pipe 62 for spacing the uprights laterally, as clearly shown in Fig. 4. If only one section is being used these rods are of proper length to extend from one side of the section to the other where they are held in place by suitable nuts. If two or more sections are arranged together, as shown in Fig. 1, the various rods 59 to 61 are of the proper length to extend through all of the sections and to receive a clamping nut at each end whereby the sections may be properly tightened, with a suitable tubular member or pipe 62 surrounding each rod for properly spacing the uprights of the various sections and also for properly spacing the sections.
- When the parts have been constructed as just described space is provided in each section for three containers 58 which are arranged at an incline. These containers are standard boxes 60 adapted to contain oranges or other fruit and in the trade are known as lugs. The sections, therefore, are constructed to receive these standard containers regardless of what kinds of fruit or vegetables are arranged therein. A cover 63 is provided for each of the containers 58, said covers being formed with a frame 64, hinged at 65, and provided with a transparent window 66 whereby the fruit or vegetables are properly protected and yet may be readily seen. The various supports 51 to 53 inclusive at the rear are adapted to receive suitable boxes or other articles 67, which may be bodily removed at any time and which are out of sight when the containers 58 are in their proper position.
- When three sections are arranged as shown in Fig. 1, there is provided a tray support 68, as shown in Fig. 6, for the space between the sections. In the structure shown in Fig. 1 there are two of these tray supports designed to support the trays 5 and 6, tray 4 being supported as heretofore described and illustrated particularly in Fig. 4. Each of the tray supports 68 is provided with a pair of supporting bars 69 and 70 formed with a number of notches 71 and prefer-

ably two connecting rods 72 are used, each of these rods being provided with a spacing tube 73. Suitable nuts are connected with the rods 72 whereby the parts are rigidly secured together.

5 After the parts have been assembled as shown in Fig. 6, they may then be placed in position as shown in Fig. 1.

The various uprights 38 and 41 to 49 inclusive are each provided with a lug or headed pin 74, as shown particularly in Figs. 4, 8 and 9. The lug or headed pin 74 on the front uprights 49 accommodate the lowermost notches 71, while the lugs on the successive other uprights accommodate the other notches. This forms a supporting frame or support for the trays 5 and 6 which are merely placed on top this construction with the sides of the trays fitting within the bars 69 and 70 so that the depending lugs 75 and 76 secured to the bottom of the trays may fit over the respective bars 72. The tray may be constructed of metal or other suitable material and in any desired way and preferably with a number of partitions 77 so that different articles may be placed in the various trays if desired.

25 In regard to the containers 58, preferably they are merely opened and the lids 63 applied thereto without removing the fruit therefrom. They are then placed in the stand as shown in Fig. 2 so that the fruit or other articles may be vended directly from the original container. In regard to the trays 4 to 6, inclusive, the grapes or other articles are removed from their original containers and arranged in the various compartments of the trays for display purposes.

35 At the top of the sections there are provided sign members, namely, the sign tray 78 and the various sign members 79. Also at the back of the sign tray 78 there is provided a box 80 having two or more hooks 81 adapted to extend through suitable slots in the respective uprights 37 and 38, whereby the box is held in proper position. The various sign members 79 are each provided with one or more supporting bars 82 and each of these bars is provided with a step 83 whereby when the parts are arranged as shown in Fig. 2 the sign member will be properly supported on the box 80. The sign tray 78 is provided with two or more hooks 84 adapted to hook over the upper ends of certain of the uprights 37 and 38 for supporting the tray in proper position. This tray, as shown in Fig. 1, is a rectangular tray and has a number of sign members 85 arranged therein. When the device is in use, preferably fruit is arranged in all of the sign members 79 and 85 and also fruit or other articles arranged in the tray 78 around the sign members 85 to present a desired background. It will be noted that the articles in the tray 78 or the various sign members may be readily removed at any time and sold.

60 Referring to the various rods 59 to 61 inclusive and the bracing pipe 62, it will be evident that other forms of bracing and supporting members could be provided, as for instance the modified forms shown in Figs. 14 and 15. From these figures it will be seen that brackets 86 and 87 are provided and the bracing bar 88 is pivotally connected by a suitable pin 89 to bracket 86 and positioned to fit into the bifurcated bracket 87. A suitable locking pin 90 may be used by being forced through the aligned apertures 91 and locking bar 88 against accidental disengagement.

When the parts have been assembled as shown in Fig. 1 the device is ready for use and may be left in this position as long as desired. In case it should be desired to store the display stand or to

ship the same the various parts may be disconnected and certain parts may be folded, as shown in Fig. 3. For instance, the box 80, tray 78, and various sign members 82 may be readily lifted out of place. The trays 4 and 5 may also be lifted out of place and then the tray support 70 removed. The various rods 59 to 61 may then be removed and the various sections 1 to 3 collapsed as shown in Fig. 3. The tables 13 and 13' may be disassembled and arranged in a small package. After the parts have been thus disassembled and arranged in one or more small packages they may be shipped as desired. By a reverse movement the parts may be reassembled and set up again, as shown in Fig. 1, so as to be ready for use.

It will be readily seen that the stand presents means for displaying the front thereof with fruit and other articles and displaying the same in a very desirable manner so as to be pleasing and, at the same time, ready of access. Along with this feature the rear part of the various sections may be used for storing boxes or other articles, while the tables 13 and 13' are ready for use when wrapping articles that have been sold, as well as ready for use in the sense of carrying boxes, wrapping paper, and the like.

I claim:

1. In a display stand for displaying fruit and other articles including a supporting section 30 formed of a plurality of spaced uprights, said uprights being disposed in pairs and the various pairs being of different heights, said pairs being disposed with the shortest pair at the front and the next shortest pair in back of the shortest pair and the remaining pairs in the same order so that the longest pair will be at the rear of the section, a connecting rod for each pair of uprights spaced from the top of the uprights, each of said rods being surrounded by a spacing tubular member, and an angle bar secured to the uprights below each of said rods and connecting said pairs in spaced relation, each of said angle bars having one end turned up to form an abutment, said angle bars coacting with said rods for supporting containers on said section with the containers held at an angle to the horizontal.

2. A display stand for displaying fruit and the like including a plurality of article-supporting sections having a series of supporting transverse bars, said sections being spaced apart, rods extending longitudinally of the stand through the sections and bridging the gap between them, said rods and said supporting bars being adapted to support receptacles thereon for displaying the contents thereof, headed pins on said sections in alignment with each other, and a tray-support located between the sections having notches for receiving said headed pins.

3. A display stand for displaying fruit and the like comprising a plurality of sections spaced apart, each section consisting of vertical and transverse members secured together and forming a framework to support receptacles, rods extending through the sections and bridging the gap between them, said rods being located in stepped formation, said rods and said transverse members acting to support receptacles at an angle for displaying articles therein, headed pins on the sides of the sections located in alignment, and tray supports located between said sections having notches for receiving the headed pins so as to be supported thereon.
